NOVELTY CASE

Filed Dec. 4, 1928

Benjamin Bernard Deitel,
By his attorney
Alexander Chesen

UNITED STATES PATENT OFFICE.

BENJAMIN BERNARD DEITEL, OF BROOKLYN, NEW YORK.

NOVELTY CASE.

Application filed December 4, 1928. Serial No. 323,603.

My invention relates to containers and, especially, to novelty containers such as vanity cases and the like.

The object of the invention is to produce a simple but rugged container, at the same time preserving a neat and artistic appearance. The construction is designed to eliminate many of the parts now used in making such articles, so that the number of tools and dies 10 in their manufacture is greatly reduced.

It is one of the characteristic features of my invention that the lid or top of the container comprises a cover plate and a framework specifically intended for some definite purpose joined to said cover plate. In my U. S. Patent No. 1,694,702, I have shown such a construction wherein the aforesaid framework, intended in that case for a mirror, is hinged to the walls of the container, and the 20 cover plate is attached to this framework. I find, however, that in some cases, for instance, where the container's use requires a comparatively heavy cover plate, as in the case of a pocket savings bank for which my construction is adapted as well as for many other forms of novelty containers, it is preferable to hinge the cover plate, and not the framework, to the walls of the container. The present invention is concerned with this modification of my device. Of course, the construction is equally applicable to the case where the lid or top of the container consists of a cover without any additional frame-work.

In the drawing, Figure 1 is a perspective view of the preferred embodiment of my invention of a vanity case simulating a book, shown as closed. Figure 2 is a plan view of the same container when open. Figure 3 is a cross section taken along the line 3—3 of Figure 1. Figure 4 is a fragmentary perspective view of the same container, open. Figure 5 is a plan view of a modification of my device, differing from the preferred form in that the above mentioned frame-work is omitted. Figure 6 is a cross section along the line corresponding to the line 3—3 of Figure 1 of the modified form of my invention illustrated in Figure 5.

Referring to the figures in detail, 1 is an open frame made of sheet metal and constituting the four walls of a container designed to simulate a book, the front and the two end walls representing the front and the end leaf edges of the book. At its nether periphery, 55 the frame 1 is bent to provide outwardly pro-

jecting flanges 2 on three sides, namely, at the front and at the two ends of the "book". To the frame 1 is attached, in the manner described further below, a cover plate 3 constituting the bottom of the container. The top 60 cover plate 3' is hinged to the back wall of the frame 1 in any suitable manner, as by means of the hinge 6. To the top cover plate 3' is attached, in a manner to be specified later, the frame-work 2' which, in this 65 particular embodiment of my invention, is a flat open frame formed of a rectangular piece of sheet metal of the same size and shape as the cover plate 3' from which a rectangular hole is cut out leaving a margin somewhat 70 wider than the flanges 2 of frame 1. A facing 4, simulating the binding of a book, covers the two plates 3 and 3' and the back wall of the frame 1. The bottom plate 3 has tongues 75 which pass through slots 18 in the back wall of frame 1 and are bent over flush with this wall. This secures the bottom plate 3 to the frame. The plate 3 is further secured thereto, together with the facing 4, by means of the channel member 5 which clamps the 80 facing and the bottom plate to the flanges 2. The facing 4 and the frame-work 2' are similarly secured to the top cover plate 3' by a second channel member 5. The walls of frame 1 may be provided with additional but 85 inwardly projecting flanges 7. The box space formed by frame 1 and the bottom plate 3 may be divided into compartments, as shown, each comprising a shallow pan, such as the pans 9 and 10, one for rouge and the other 90 for face powder, separated and, at the same time, held in place, by a cross piece 11. Pads containing rouge and powder may be provided, as indicated in the drawing by dotted lines and designated by the numerals 12 and 95 13. Various means may be used to effect closure. Merely as a matter of illustration, a simple form of snap arrangement 8 is shown, either secured to the frame-work 2', as in the preferred embodiment, or to the top 100 cover plate 3', as in the modification shown in Figures 5 and 6. The inward edges of the frame-work 2' are formed into the bezels 14, for which purpose the margin of this frame-work has been left wide enough, as stated 105 above. A mirror 15 is set within the bezels 14 and rests against the top cover plate 3'. The bezels 14 are so spaced that when the container is closed they can pass the inwardly projecting flanges 7 of frame 1. The fac- 110

ing 4 is turned inwardly at 16 in a manner similar to that common in the art of book binding.

It is to be understood that the shape of the 5 container need not be rectangular, nor is it necessary for the top and bottom covers to be of the same shape or size. As already stated, the construction is applicable for many purposes, and, while only a vanity case is 10 shown and specifically described, the invention may clearly be used in the making of a great variety of other containers of similar type.

I claim:

15 1. A container comprising an open frame constituting the walls thereof, outwardly projecting flanges on said frame at one of its peripheries, a cover conforming to the shape of said frame and constituting the bottom of 20 said container, a cover hinged to said frame and constituting the top of said container, a facing extending over said top and bottom covers and over the hinged portions of said frame, a channel member clamping said fac- 25 ing and said bottom cover to said flanges, and a channel member clamping said facing to the edges of said top cover.

2. A container comprising an open frame constituting the walls thereof, outwardly projecting flanges on all but one of said walls, 30 slots in the remaining one of said walls, a cover conforming to the shape of said frame and constituting the bottom of said container, tongues on said cover passing through said 35 slots and bent flush with said slotted wall, a cover hinged to said slotted wall and constituting the top of said container, a facing extending over said top and bottom covers and over said slotted wall, a channel member 40 clamping said facing and said bottom cover to said flanges, and a channel member clamping said facing to the edges of said top cover.

3. A container comprising an open frame constituting the walls thereof, outwardly projecting flanges on said frame at one of its peripheries, a cover plate conforming to the 45 shape of said frame and constituting the bottom of said container, a cover plate hinged to one of said walls and constituting the top of 50 said container, a frame-work shaped to conform with said top, a facing extending over

said top and bottom cover plates and over 55 said hinged wall, a channel member clamping said facing and said bottom cover plate to said flanges, and a channel member clamping said facing and said frame-work to the edges of said top cover plate.

4. A container simulating a book and comprising an open frame constituting the walls thereof, the front and the two end walls representing the front and the end leaf edges of 60 said book, outwardly projecting front and end flanges on said frame along one of its peripheries, a cover conforming to the shape of said frame and constituting the bottom of 65 said container, a cover hinged to the back wall of said frame and constituting the top of said container, a facing extending over said top and bottom covers and over said back wall simulating the binding of a book, a 70 channel member clamping said facing and said bottom cover to said flanges, the entire length thereof, and a channel member clamping said facing to the front and end edges of 75 said top cover.

5. A vanity case simulating a book and comprising an open frame constituting the walls thereof, the front and the two end walls representing the front and the end leaf edges of 80 said book, outwardly projecting front and end flanges on said frame along one of its peripheries, inwardly projecting flanges along its other periphery, slots in the back wall of 85 said case, a cover plate conforming to the shape of said frame and constituting the bottom of said case, tongues on said cover plate passing through said slots and bent flush with said back wall, a cover plate hinged to said back wall and constituting the top of said 90 case, a frame-work shaped to conform with said top disposed thereunder, bezels on said frame-work adapted to hold a mirror and fitting within said inwardly projecting flanges, a facing extending over said top and bottom cover plates and over said back wall simulat- 95 ing the binding of a book, a channel member clamping said facing and said bottom cover plate to said outwardly projecting flanges the entire length thereof, and a channel member clamping said facing and said frame-work to 100 the edges of said top cover plate.

BENJAMIN BERNARD DEITEL.
